UNITED STATES PATENT OFFICE.

EDWARD G. THOMAS, OF TOLEDO, OHIO, ASSIGNOR TO TOLEDO SCALE COMPANY, OF TOLEDO, OHIO, A CORPORATION OF NEW JERSEY.

DESIGN FOR A WEIGHING-SCALE CASING.

Application filed December 31, 1923. Serial No. 8,196. Term of patent 14 years.

To all whom it may concern:

Be it known that I, EDWARD G. THOMAS, a citizen of the United States, residing at Toledo, in the county of Lucas and State of Ohio, have invented a new, original, and ornamental Design for Weighing-Scale Casings, of which the following is a specification, reference being had to the accompanying drawing, forming a part thereof.

Figure I is a front view of the weighing scale casing, showing my new design.

Figure II is a side view thereof.

I claim:

The ornamental design for a weighing scale casing as shown.

EDWARD G. THOMAS.
